UNITED STATES PATENT OFFICE.

ERNEST R. MILLER, OF NEAR CENTERVILLE, OHIO.

CLUTCH-PEDAL LOCK FOR TRACTORS.

Application filed August 8, 1921. Serial No. 490,446.

To all whom it may concern:

Be it known that I, ERNEST R. MILLER, a citizen of the United States, residing in the county of Montgomery near the town 5 of Centerville, State of Ohio, have invented certain new and useful Improvements in Clutch-Pedal Locks for Tractors, of which the following is a specification.

The principal object of my invention is 10 to provide for tractors, and more particularly those of the Fordson type, simple and efficient means for automatically holding the clutch in a released position after it has been shifted by foot pressure.

15 Other important and incidental objects will be brought out in the following specification and particularly set forth in the subjoined claims.

In the accompanying drawings, Figure 1 20 is a side elevational view of a light tractor equipped with my new clutch pedal lock. Figure 2 is a side view of the clutch pedal shifting means before being moved by foot shifting pressure to their "over center" or locking position. Figure 3 is a side view of said means in their "over center" position. And Figure 4 is a top plan view of said means.

Throughout the specification and drawings, similar reference characters denote corresponding parts.

Referring to the accompanying drawings for a detailed description of one form of embodiment of my invention, the numeral 35 1 designates a light tractor, and 2 the clutch pedal thereof. Bolted to the lower part of a foot bracket 3 secured to the tractor 1 below the clutch pedal 2, is the front end of a bar 4. The latter has a crank-shaped 40 rear portion 5 that is attached by a bolt 6 to the rear side portion of the tractor. (See Figures 1 and 4.)

Pivotedly secured by a stud rivet 7 or other suitable fastening element to the middle portion of the bar 4, is an arm 8 to the lower end of which there is attached, by stud rivet 9, an angle piece 10. The rivet 9 passes through an elongated vertical hole 11 provided in said angle piece to allow 50 for slight play. (See Figure 2.)

Passing downwardly through a hole in the horizontal portion of the angle piece 10 is the threaded lower end of a connecting rod 12. Applied to the threaded end of 55 the latter, one on each side of the horizontal portion of the angle piece 10, are two nuts

13, 13. The latter, when loosened, permit a longitudinal adjustment of the rod 12 through the angle piece 10, after which they are adapted to be turned to tightly grip the horizontal flange portion of said angle piece for the purpose of firmly securing the rod thereto. (See Figures 1, 2 and 4.)

At its upper end the rod 12 preferably terminates in a ball portion 14 that is received by a socket member 15 that projects downwardly from a cross bar 16. The latter is adapted to be firmly secured by U bolts 17 to the horizontal foot-receiving part 18 of the clutch pedal 2. The ball 70 and socket connection just described enables the rod 12 to be easily secured to foot pedals of different angles for a purpose now to be described.

When sufficient pressure is exerted upon 75 the clutch pedal 2 by the foot to throw the latter to its clutch-releasing position, the arm 8 will be thrown "over center" by the rod 12 to the position shown in Figure 2. The movement of the arm 8 to this position 80 is assisted by a spring 19 connected between said arm and the bar 4, although the arm may be thrown "over center" without the employment of a spring or other means 85 to assist it. After the clutch pedal 2 has been moved to its clutch-releasing position, the movement of the arm 8 will be stopped by a stud rivet 20 secured to the bar 4 in front of the rivet 7. Since the arm 8 is now "over center," it will hold the 90 clutch in its released position after the driver's foot has been removed from the clutch pedal 2.

The arm 8 may be forced back to its 95 original position shown in Figure 2 by foot pressure exerted directly upon it, but for the purpose of more conveniently returning it to its original position, there is pivoted to the bar 4 by a stud rivet 21, a foot 100 lever 22. Secured to the lower end of the latter is a stud 23 on which there is mounted a roller 24. Now when foot pressure is applied to the lever 22, the roller 24 will engage the arm 8 to move it "over center" 105 to its original position shown in Figure 2, thereby permitting the clutch pedal 2 to be returned to its original position.

The device I have shown and described is simple in construction, it may be economically manufactured, and it may be easily 110 applied to a tractor.

I do not wish to be limited to the details

of construction and arrangement herein shown and described, and any changes or modifications may be made therein within the scope of the subjoined claims.

5. Having described my invention, I claim:

1. In a self-propelled vehicle of the type described, the combination with a clutch pedal, of an arm pivotally secured to said vehicle, an angle piece secured to the free 10 end of said arm, a rod connected at its upper end to the clutch pedal, a lower threaded end on said rod projecting downwardly through the horizontal portion of said angle piece, and two nuts on the threaded end of 15 said rod, one on each side of the horizontal portion of said angle piece, for the purpose specified.

2. In a self-propelled vehicle of the type described, the combination with a clutch 20 pedal, of an arm pivotally secured to said vehicle, a vertical rod connected at its lower end to said arm, a ball on the upper end 25 of said rod, a horizontal member secured to said clutch pedal, and a socket piece projecting downwardly from said horizontal member, to receive said ball end of the rod, for the purpose specified.

3. In a self-propelled vehicle of the type described, the combination with a clutch 30 pedal, of a horizontal bar secured to said vehicle, an arm pivotally secured to said bar, means connected between said clutch pedal and said arm, whereby, when the clutch 35 pedal is depressed, said arm will be thrown "over center" to hold said clutch pedal down, and a stop element on said bar adapted 40 to be engaged by said arm to limit its forward movement when the clutch pedal has reached the limit of its downward movement.

4. In a self-propelled vehicle of the type described, the combination with a clutch pedal, of a horizontal bar secured to said vehicle, an arm pivotally secured to said bar, means connected between said clutch 45 pedal and said arm, whereby, when the clutch pedal is depressed, said arm will be thrown "over center" to hold the clutch pedal down, and a spring connected between said arm and bar to assist in pulling said 50 arm "over center."

5. In a self-propelled vehicle of the type described, the combination with a clutch pedal, of a horizontal bar secured to said vehicle, an arm pivotally secured to said bar, 55 means connected between said clutch pedal and said arm, whereby, when the clutch pedal is depressed, said arm will be thrown "over center" to hold the clutch pedal down, and a foot lever pivoted to said horizontal 60 bar in a position to engage said arm to return it to its original position.

6. In a self-propelled vehicle of the type described, the combination with a clutch pedal, of a horizontal bar secured at its 65 front end to said vehicle, a crank shaped rear end on said bar secured to said vehicle below the clutch pedal, an arm pivotally secured to the middle portion of said bar below the clutch pedal, an angle piece secured 70 to the free end of said arm, a rod secured at its lower end to said angle piece, a cross bar to which the upper end of said rod is secured, and clamping means for securing said cross bar to the clutch pedal. 75

In testimony whereof I have hereunto set my hand this 5th day of August, 1921.

ERNEST R. MILLER.

Witness:

HOWARD S. SMITH.
